UNITED STATES PATENT OFFICE.

JAMES C. SPRAGUE AND ALEXANDER G. JOHNSTON, OF PATTEN, MAINE.

LOG-LOADER.

1,363,930.

Specification of Letters Patent. Patented Dec. 28, 1920.

Application filed September 3, 1919. Serial No. 321,426.

To all whom it may concern:

Be it known that we, JAMES C. SPRAGUE and ALEXANDER G. JOHNSTON, citizens of the United States, and residents of Patten, in the county of Penobscot and the State of Maine, have invented certain new and useful Improvements in Log-Loaders, of which the following is a specification.

This invention relates to a device for facilitating the loading and handling of logs, and is especially designed for the handling of four foot pulp logs and ties.

The invention consists in the novel features of construction hereinafter described, pointed out in the claim, and shown in the accompanying drawings, in which:—

Figures 1, 1^a, are a plan view.

Figs. 2, 2^a are a side elevation.

Fig. 3 is a front elevation.

20 In these drawings 1 designates sled runners having thereon a log receiving platform 2, and in advance of said platform a bolster 3 on which is mounted the rear end portion of a platform 4, the forward end of which is mounted on runners 5, said runners having a bolster 6, the under side of which is cut away between the runners to allow clearance, as shown in Fig. 3.

On the platform 4 are mounted suitably braced standards 7. On a shaft 8 carried by the rear portion of the runners 1 are parallel plates 9, which form the body portion of the conveyer. The inner corners of these plates are cut out as at 10. Outer parallel bars 9^a are pivotally mounted on the shaft 8, their outer ends being connected by a shaft 18 referred to more specifically hereafter. At the forward end of the runners 1 are parallel shafts 11 and 12. Fixed 35 on the shaft 11 is a pulley 13 and a gear wheel 14. On the shaft 12 is a pinion 15 meshing with the gear wheel 14, and sprocket wheels 16.

Sprockets 16^a are mounted on the shaft 8, 45 and chains 17 run over said sprockets and over and under the platform 2. The rear end of the conveyer plates 9 carry a shaft 18. Sprockets 19 are mounted on the shaft 8 and sprocket 19^a on the shaft 18, these 50 sprockets being arranged respectively in the cut out corner portions of the plates 9. Loading chains 20 run over the sprockets 19 and 19^a and over the plates 9, the mounting of the sprockets for the chains 20 in

the cut out portions of the plates allowing 55 for this.

The rear portion of the conveyer is provided with a transverse projecting cross member 21, carrying pulleys 22, over which run the cables 23 for raising and lowering 60 the conveyer. These cables work over suitably arranged pulleys 24 carried by the standards. The ends of the cables are secured respectively to rings 25 and to a roller 26, carried by the platform 4, and operated, 65 to adjust the conveyer by any suitable means.

A tongue 27 is employed for moving the device from place to place, and said tongue may be attached in any manner and to either 70 end of the device.

A suitable engine, not shown, is placed where most convenient, as on the platform 4, and drives the pulley 13.

In cutting pulp wood it is common to 75 form large stacks or piles of the wood, in four foot lengths, and then haul from said piles to a mill or railway. To load from these piles in the usual way would require two shifts of men, one to throw the logs 80 from the pile and another to load them on the sled. As such hauling is done during the winter months a sled is the only practical method of transport. By use of our device the amount of labor is cut in half, a 85 matter of vital importance at the present time. The sled is backed to the pile, the logs placed on the conveyer and they then travel downwardly to the rear platform where they are taken up by the chains 17 90 and carried along the rear platform. One man can swing the logs with a spike from the chains and into position on the sled, parallel to and between the chains. As the pile decreases in size the conveyer is 95 gradually lowered so that its upper end will remain approximately about the height of the pile of logs.

What we claim is:—

As a new article of manufacture, a log 100 loading and conveying device comprising forward and rearward sled runners, a platform on the forward runners, a log receiving platform on the rear runners, sprocket wheels mounted at each end of the rear platform, parallel chains running over said sprocket wheels and over and under the said platform, the upper flights adapted to travel 105

toward the forward platform, a shaft carried by the rear portion of said rear runners, and a conveyer comprising parallel plates pivotally mounted on said shaft and 5 parallel chains adapted to travel longitudinally over the plates, common means for operating all of said chains, and means car-

ried by the front platform for adjusting said conveyer.

In testimony whereof we affix our signatures.

JAMES C. SPRAGUE.
ALEXANDER G. JOHNSTON.
